UNITED STATES PATENT OFFICE.

MICHAEL J. O'BRIEN, OF PHILADELPHIA, PENNSYLVANIA.

DESIGN FOR A STAND FOR DRAINING GLASSES.

SPECIFICATION forming part of Design No. 33,504, dated November 6, 1900.

Application filed September 28, 1900. Serial No. 31,450. Term of patent 14 years.

To all whom it may concern:

Be it known that I, MICHAEL J. O'BRIEN, citizen of the United States of America, and a resident of the city and county of Philadelphia and State of Pennsylvania, have invented and produced a new and original Design for Stands for Draining Glasses, of which the following is a specification, reference being had to the accompanying drawings, forming part thereof.

My invention relates to a new and original design for a stand for draining glasses, of which the following is a specification.

Referring to the accompanying drawings, Figure 1 illustrates an end view of a stand for draining glasses, showing my new design. Fig. 2 represents a plan view of the same, and Fig. 3 shows a section on the line 3 3 of Fig. 2.

As shown in the drawings, the leading or material feature of design consists of a rectangular plate having an inwardly-curved semicircular end, the plate being formed of a series of ribs crossing each other at such an angle as to form a number of diamond-

shaped spaces, as shown in Fig. 2 of the drawings. The ribs A and A' are connected to and form part of the outer frame C, which is practically rectangular in shape, except at one of the short ends of the rectangle, which is curved inwardly in the form of a semicircle, as shown indicated by the letter D in the several views of the drawings.

At the four corners of the stand are arranged short legs E, by which means the draining-stand is supported a short distance above a table, washstand, or other means of support.

Having described my invention, what I claim as new, and desire to secure by Letters Patent, is—

The design for a stand for draining glasses, as herein shown and described.

Signed at Philadelphia, Pennsylvania, this 26th day of September, 1900.

MICHAEL J. O'BRIEN.
